CLAIM

The ornamental design for an operating unit with display, as shown and described.

DESCRIPTION

FIG. 1 is a perspective view of the operating unit with display;

FIG. 2 is a front view thereof;

FIG. 3 is a left view thereof;

FIG. 4 is a right view thereof;

FIG. 5 is a bottom view thereof;

FIG. 6 is a top view thereof; and,

FIG. 7 is a rear view thereof.

The broken lines in FIGS. 3 and 4 depict parts of the operating unit with display that form no part of the claim.

1 Claim, 7 Drawing Sheets(56)
